UNITED STATES PATENT OFFICE.

HARRY R. ZIMMER, OF LOS ANGELES, CALIFORNIA.

DESIGN FOR A RADIUM-ACTIVATING DEVICE.

Application filed November 7, 1927. Serial No. 24,027. Term of patent 14 years.

To all whom it may concern:

Be it known that I, HARRY R. ZIMMER, a citizen of the United States of America, residing at Los Angeles, in the county of Los Angeles and State of California, have invented a new, original, and ornamental Design for a Radium-Activating Device, of which the following is a specification, reference being had to the accompanying drawing, forming a part thereof.

Figure 1 is a view in front elevation, and Figure 2 is a top plan view, showing my new design.

I claim:—

The ornamental design for a radium activating device as shown.

HARRY R. ZIMMER.
